US0D1102295S

(12) **United States Design Patent** (10) Patent No.: **US D1,102,295 S**
(45) Date of Patent: ** Nov. 18, 2025

(54) **SET OF BANDS FOR A WATCH OR SMART WATCH**

(71) Applicant: **Fitbit, Inc.**, San Francisco, CA (US)

(72) Inventors: **Benjamin Patrick Robert Jean Riot**, San Francisco, CA (US); **Brian Dennis Paschke**, San Francisco, CA (US); **Eric John Fairbanks**, Lafayette, CA (US); **Anthony Gerald Kern**, Pleasant Hill, CA (US); **Jonah Avram Becker**, San Francisco, CA (US); **Ching-Lung Hsu**, Taipei (TW); **Stephen Ronald Smilovitz**, Belmont, CA (US); **Jens Mitchell Nielsen**, San Francisco, CA (US); **Christopher Alan Porter**, Tiburon, CA (US)

(73) Assignee: **Fitbit, Inc.**, San Francisco, CA (US)

(**) Term: **15 Years**

(21) Appl. No.: **29/767,333**

(22) Filed: **Jan. 21, 2021**

Related U.S. Application Data

(63) Continuation of application No. 29/712,571, filed on Nov. 8, 2019, now Pat. No. Des. 909,225.

CLAIM

The ornamental design for a set of bands for a watch or smart watch as shown and described.

DESCRIPTION

FIG. 1 is a top side isometric view of our new design for a set of bands for a watch or smart watch.

FIG. 2 is a top side plan is a view of FIG. 1.

FIG. 3 is a bottom side plan view of FIG. 1.

FIG. 4 is a left side elevation view of FIG. 1.

FIG. 5 is a right side elevation view of FIG. 1.

FIG. 6 is a front side elevation view of FIG. 1; and,

FIG. 7 is a back side elevation view of FIG. 1.

The features shown in dash-dot lines in the drawing depict portions of the bands. The dash dot dash lines define the bounds of the claimed design. The broken lines form no part of the claimed design.
